UNITED STATES PATENT OFFICE.

RANDALL B. BAKER, OF WATERTOWN, MASSACHUSETTS, ASSIGNOR TO THE HOLTZER-CABOT ELECTRIC COMPANY, OF ROXBURY, MASSACHUSETTS, A CORPORATION OF MASSACHUSETTS.

TELEPHONE HEADSET.

Application filed February 23, 1923. Serial No. 620,568.

To all whom it may concern:

Be it known that I, RANDALL B. BAKER, a citizen of the United States, residing at Watertown, in the county of Middlesex and 5 State of Massachusetts, have invented certain new and useful Improvements in Telephone Headsets; and I do hereby declare the following to be a full, clear, and exact description of the invention, such as will 10 enable others skilled in the art to which it appertains to make and use the same.

The present invention relates to an improvement in telephone head sets.

A head set comprises a pair of telephone 15 receivers, a head band or a pair of head bands extending over the head and serving to connect the two receivers together, and some contrivance for attaching the receivers to the ends of the head bands.

20 The object of the present invention is to produce a device for connecting receivers and head bands which is simple in construction, not easily disorganized or got out of order, and capable at the same time of adjustment so that the receivers may be 25 adjusted with respect to the position of the head bands to accommodate varying positions of the receivers with relation thereto.

30 In the accompanying drawings illustrating the preferred form of the invention, Fig. 1 is a perspective view of the head set, the receivers being omitted; Fig. 2 is an elevation of the connecting device; Fig. 3 is a vertical sectional elevation of the same; Fig. 4 is a front elevation of the clamp cup; Fig. 5 is a rear elevation of the clamp follower; and Fig. 6 is a view of the spring removed.

35 The illustrated embodiment of the invention is described as follows: The head bands 10 are provided at their ends with wires 11 by which their ends are attached to the connecting device. The connecting device comprises a clamp cup 12, a clamp follower 13, held together by a screw 14, between which clamp members the ends of the wires 11 are clamped, and a spring follower 15, which encloses a spring 16. This connecting device carries the stem 17 of the receiver fork, between the arms 18 of which is pivotally 40 supported the receiver.

45 The clamp cup comprises a disk 20 provided with a flange 21 or lip at its edge. This flange is cut away at 22 to form notches through which the wires 11 of the head 50 bands enter the space between the clamp cup

and clamp follower. The clamp follower consists of a disk 23 rabbeted at 24. The diameter of the disk is slightly less than the inside diameter of the clamp cup flange, so that it is received within the flange of the 60 clamp cup. The ends of the wires 11 extend into the space between the clamp cup and the clamp follower and are bent to conform to the annular space formed between the bottom of the rabbet 24 and the front face 65 of the clamp cup disk. From the center of the clamp follower disk there rises the post 25, which is provided with a hole to receive the stem 17 of the receiver fork. The screw 14 is received in a central screw-threaded 70 hole in the clamp follower disk, the clamp cup being provided with a hole to receive the head of the screw.

75 The clamp cup, clamp follower, clamp screw and head band wires are assembled in the following manner. The curved ends of the wires are laid on the clamp cup in the position shown in Fig. 2, the clamp follower is put in place, the screw 14 is screwed up tightly, and then the clamp disk is supported 80 on an anvil or base and a heavy pressure is exerted on the clamp follower disk which forces the clamp follower and clamp cup together, indenting the surfaces of both cup and follower where the ends of the wires 11 85 lie. Thus in the clamp cup are formed two head band wire recesses 26, and in the clamp follower are formed two head band wire recesses 27. The screw 14 is then again screwed up tight and the head band wires 90 are thereby rigidly secured in place in the clamp. If for any purpose it is desired to disassemble the clamp to remove the head bands it is easily done by removing the clamp screw 14. Then the clamp may be re-assembled and the wires of the head band 95 will locate themselves in the wire recesses of the cup and follower, and when the screw is tightened up again the clamp will be 100 firmly attached to the head band wires.

105 The stem 17 of the receiver fork slides easily in the hole in the end of the post 25, and the spring follower is pressed by the spring 16 against the stem so as thereby to hold the fork stem frictionally in any given position of adjustment. The ends of the stem 17 of the receiver forks are provided with screws 28 which are slightly larger in diameter than the diameter of the stem 17, and therefore slightly larger than the holes 110

in the posts 25, so that the stem 17 of the receiver forks cannot unintentionally be disengaged from the connecting device. But if it is desired to disconnect it for any reason, 5 it may be easily accomplished by removing the screw 28, whereupon the stem 17 may be slid out through the hole in the post 25. This frees the spring follower and spring without detaching the head band from the 10 clamp. The stem 17 of the receiver forks is easily reinserted in place by first applying the spring to the post of the clamp follower, then putting on the spring follower and holding it down with the fingers while the 15 stem 17 is thrust through the hole in the post 25, after which the screw will be replaced in the end of the stem 17 and the connection is again made permanent.

It will be observed that the clamp for securing the head bands to the connecting device may be dismantled without removal of the receiver forks from the connecting device. It will also be observed that the receiver forks may be removed from the connecting device without disturbing the attachment of the clamp to the head bands. The connecting device commends itself by reason of these facts, and also by reason of the fact that it is devoid of any projecting 25 part or device which would catch in the hair of the wearer of the head set. Also that the head band may be put in place on the head and the receivers may easily be adjusted with relation thereto by simply holding the 30 clamps while the receivers are moved up and down until the correct position is secured. It will also be observed that when the end wires 11 are clamped between the clamp cup and the clamp follower the fact that the end 35 wires lie in recesses in these two parts prevents relative turning of the follower with respect to the cup, thereby maintaining the angular position of the head band and receiver fork stem. The recesses in the flange 40 of the clamp cup would suffice to prevent the turning of the cup with respect to the head bands, and the recesses in the surface of the follower embracing as they do the end wires of the head bands would prevent 45 the turning of the follower with respect to the cup, and therefore with respect to the head band. The end wires act as keys to lock the clamp members from relative rotational movement.

Having thus described the invention, what is claimed is:

1. A telephone head set having, in combination, a head band provided with an end portion, a receiver carrier provided with a 55 stem, a clamp connection provided with a hole to receive the stem and a recess to receive the end portion of the head band,

means for clamping the end portion in the recess of the clamp connection, and resilient means for holding the stem thereto. 65

2. A clamp connection for telephone head sets having, in combination, a clamp cup, a clamp follower, the clamp cup and clamp follower being provided with end wire recesses adapted to receive and locate the end 70 wire of the head band, and a screw for clamping the follower and cup together on the end portion of the head band, said recesses preventing turning of the clamp follower with respect to the clamp cup. 75

3. A clamp connection for telephone head sets having, in combination, a clamp cup provided with a flange, a notch in the flange adapted to permit the entrance of the end 80 wire of a head band into the cup, a clamp follower adapted to be received in the cup, said clamp follower being provided with an end wire recess to receive the end wire, a screw for clamping the cup and follower together, such recess acting to prevent turning of the follower with respect to the cup. 85

4. A clamp connection for telephone head sets having, in combination, a clamp cup and follower, between the surfaces of which the end portion of a head band is adapted to be 90 received, means for clamping the two parts together so that they are incapable of turning with respect to each other, said follower being provided with a post having a hole in it to receive the stem of the receiver carrier, 95 and a spring contrivance to press against the stem and hold it in adjusted position.

5. A telephone head set having, in combination, a head band provided with a non-straight end wire, a clamp consisting of two 100 members between which the end wire is received, such clamp members having head band wire recesses fitting the non-straight portion of the wire for holding it from movement, a screw for holding the two 105 clamp members together, a receiver carrier, and means for securing the carrier to the clamp.

6. A telephone head set having, in combination, head bands provided with end wires, 110 a receiver carrier, a clamp cup provided with a flange having notches for receiving the end wires, a clamp follower provided with a post having a hole for receiving the receiver carrier, a screw for holding the clamp cup and follower together, the cup and follower being provided with recesses for holding the end wires to prevent relative turning of the cup and follower, a spring follower, and a coil spring taking between the clamp follower and the spring follower for resiliently 115 holding the receiver carrier on the clamp. 120

RANDALL B. BAKER.
